UNITED STATES PATENT OFFICE

2,683,557

PACKAGING MACHINE

Ray S. Jenney, Battle Creek, Mich., assignor to
 Kellogg Company, Battle Creek, Mich., a corporation of Delaware

Application December 23, 1950, Serial No. 292,517

19 Claims. (Cl. 226—16)

1

This invention relates to improvements in packaging machines and refers particularly to a machine for automatically packaging a predetermined number of individual articles in a predetermined positional relationship with respect to each other in a carton or box.

The present invention is particularly adaptable for packaging shredded wheat biscuits and for purposes of illustration the machine will be described, and its operation explained, in conjunction with the packaging of shredded wheat biscuits. It is to be understood, however, that the present invention is not to be limited to the packaging of this specific article, nor is it intended to be limited to the packaging of food products generally, since the invention will find use wherever it may be desired to package individual articles, whatever their nature, which are generally of the size and shape of a shredded wheat biscuit and where it is desired to package the articles in a predetermined positional relationship within a preformed package or carton.

In one manner of packaging shredded wheat biscuits, the biscuits are packaged fifteen to a package, the biscuits being arranged in five tiers, three biscuits to a tier. The biscuits are disposed in the package with their sides of greatest area parallel to the top and bottom of the package; their length disposed at right angles to the sides of the package and their width disposed at right angles to the ends of the package. In addition, between adjacent tiers of three biscuits each, a separator, usually constructed of corrugated fibrous material, conformable generally with the sectional area of the package, is disposed.

One of the objects of the present invention is to package individual articles in a fashion generally similar to the manner of packaging shredded wheat biscuits as hereinbefore described. Of course, obvious modifications of the machine hereinafter described can be made to modify this method of packaging, for instance, the number of articles per tier may be changed and/or the number of tiers per package may be changed and, if desired, the use of separators between adjacent tiers may or may not be dispensed with.

In copending application for United States Letters Patent Serial No. 184,544, filed September 13, 1950, in the names of Ray S. Jenney and Robert E. Fetherston, a conveyor is shown and described for moving, in a continuous fashion, individual articles, such as shredded wheat biscuits, to a packaging machine or a separating

5 and aligning machine such as described in co-pending application for United States Letters Patent Serial No. 194,166, filed November 4, 1950, in the names of Ray S. Jenney, Robert E. Fetherston, and Glen Miller. In the first mentioned application for United States Letters Patent the movement of shredded wheat biscuits moving from an oven in a row by row movement is converted to a sequential or series travel, where the 10 biscuits follow each other in seriatim. In the second mentioned application for United States Letters Patent sequentially traveling articles such as shredded wheat biscuits are diverted in a predetermined sequential fashion so as to move in a row by row movement or a movement substantially resembling a row by row movement. In this application for patent the articles are oriented so that during their movement they move in the direction of their longitudinal axes. 15 If desired, the present invention may be employed in conjunction with the machines described in the two above-mentioned applications for United States Letters Patent. However, it is to be understood that the present invention is not to be limited to this specific environment since the concepts thereof may be employed independently of any specific type of feed mechanism.

Briefly described, the present invention contemplates receiving a predetermined number of articles which are carried in separate parallel passageways, the number of passageways corresponding to the number of articles which are adapted to be packaged in the carton. The passageways are in turn segregated into groups of passageways, the number of groups being equal to the number of tiers of articles in the carton. The number of passageways constituting each group being equal to the number of articles constituting a tier. The articles thus carried are fed to a number of packaging stations corresponding to the number of tiers in the finished package, one group of passageways leading to each packaging station. A plurality of package forms are intermittently carried transverse to the movement of the articles and mechanism is provided for charging the articles in each group of passageways to individual package forms during each dwell of movement of the packaging forms. In this fashion a tier of articles is charged to a package form in each of the packaging stations. The package forms continue their intermittent movement and a preformed carton envelopes the forms whereby the articles are disposed in the preformed carton in a predetermined positional relationship. During the 20 25 30 35 40 45 50 55

charging of the various tiers of articles in the packaging stations means may be employed, if desired, for interposing spacers between adjacent tiers of articles. The operation, features and advantages of the present invention will be more apparent from the accompanying drawings and following detailed description.

In the drawings,

Fig. 1 is a top plan view of the packaging machine embodying the concepts of the present invention.

Fig. 2 is a front elevational view of the machine, looking in the direction of the arrow in Fig. 1.

Fig. 3 is a sectional view taken on line 3—3 of Fig. 1 showing the opposite side of the front portion of the machine shown in Fig. 2.

Fig. 4 is a sectional view taken on line 4—4 of Fig. 6.

Fig. 5 is a detailed view illustrating portions of the elements of Fig. 4 in a different position or phase of operation.

Fig. 15 is a transverse sectional view taken on line 15—15 of Fig. 14.

Fig. 16 is a sectional view taken on line 16—16 of Fig. 14.

Fig. 17 is a schematic wiring diagram showing the electrical connections of various of the solenoids employed.

Referring in detail to the drawings, 1—1 indicates opposite frame members of the packaging machine. A transverse channel iron 2 is supported by the frame members 1—1 and carries a beam 3 of T section. A plate 4 is secured to a portion of the beam 3 and carries at its opposite ends, end plates or standards 5. A plurality of adjacent rolls 6 are journaled at their opposite ends in the opposite standards 5, said rolls all being adapted to be driven in the same angular direction, that is, in a clockwise direction as viewed in Fig. 4. A shaft 7 is journaled in suitable bearings 8—8 carried by the transverse channel iron 2, the rolls 6 being driven by suitable gear trains 9 and 10, certain of said gears not being shown. The arrangement, however, is such that rolls 6 and shaft 7 rotate in the same angular direction, the rolls 6 being driven from the shaft 7.

A motor 11 is mounted upon one of the frame members 1, said motor being adapted to drive shaft 7 by means of sprocket chain 12 trained around motor sprocket wheel 13 and shaft sprocket wheel 14. A plurality of pulleys 15 are mounted upon shaft 7 and around each pulley a belt 16 is trained. As will be hereinafter more fully described, the belts 16 are conveyor belts

for moving articles toward the packaging stations. The articles are carried to the upper passes of the belts 16 over rolls 6 which function as a bridge from a feed conveyor 17 which at the end of its upper pass is trained around roll 18. As has been hereinbefore described the present machine may have the articles to be packaged delivered thereto in any suitable manner, for instance, by the mechanisms shown and described in the applications for patent hereinbefore identified. Of course, the present invention is not to be limited to any specific feed mechanism, but in the handling of shredded wheat biscuits those mechanisms described in said applications for patent have been found to be particularly suitable.

For purposes of description, the conveyor 17 is shown as the means for delivering the articles to the present machine, said conveyor intended to represent any suitable means for feeding the articles to the machine. Further, for purposes of description only and not by way of limitation, the articles handled and packaged by the present machine are shown as being conventional shredded wheat biscuits.

As has been hereinbefore described shredded wheat biscuits may be packaged fifteen to a package, the biscuits being disposed in the package in five tiers, three biscuits to a tier. The concept of the present machine is such that it is divided into a plurality of duplicate units equal in number to the number of tiers in the package, namely, five duplicate units. In general, the entrances to the five units are designated (Fig. 1) by the reference numerals 19, 20, 21, 22 and 23.

Each unit comprises three parallel conveyor belts 16 trained around rolls 15. Partition plates 24 supported at one end upon the T-beam 3 and at the other end upon transverse bar 25, separate each group of three belts 16, the bar 25 being, in turn, supported upon vertical frame members 26. Between the partition plates 24 are partitions 27 which separate adjacent belts 16 from each other. Belts 16, at the end of their upper passes are trained around rolls 28 carried by transverse shaft 29 carried by partition plates 24. Each of the belts 16 at its lower pass wraps around a belt tightening roll 30, carried by an arm 31 which, in turn, is pivotally mounted upon transverse shaft 32. Each belt then wraps around an idler roll 33 and returns over roll 15.

A supporting plate or platform 34, carried by opposite brackets 35, is mounted immediately beneath the upper passes of the belts 16 included between adjacent partition plates 24, the brackets 35 being secured to said partition plates by any suitable fastening means, such as screws 36. The belts 16, at their upper passes slide upon and are supported by the plates 34. Forward of each plate 34 and in substantial planar alignment with the upper passes of the belts 16, is a stationary platform 37 supported by brackets 38 secured to opposite partition plates 24.

A cover strip 39 is positioned above the upper pass of each of the belts 16, each of said strips carrying spaced lugs 40. A pair of rods 41 and 42 are disposed transversely with respect to the belts 16, being secured in partition plates 24, each of said rods carrying a plurality of arms 43 and 44, respectively. The arms 43 and 44 are pivotally secured to lugs 40 of the strips 39 and function to suspend said strips in spaced relationship above the belts 16. Arms 43 and 44 are adjustably positioned upon rods 41 and 42 respectively and may be so fixed with respect to the rods as

to position the strips at a desired elevation above the belts. In practice the strips 39 are positioned above the belts at a distance slightly greater than the thickness of the articles carried upon the belts, whereby a plurality of substantially closed passageways are provided, being defined by the partition plates 24, the partitions 27, the belts 16 and the strips 39. Each of the strips 39 at its rear end extends over a roll 6 and terminates at its forward end over the rear portion of the stationary platform 37.

For purposes of description it is assumed that a plurality of articles, shredded wheat biscuits 45, are positioned end to end upon each conveyor belt 16 (Fig. 4). The movement of the biscuits upon the belt will push a plurality of the biscuits, illustrated as two in number, upon the stationary platform 37. As will be hereinafter more fully described, the biscuits upon the belts 16 must be contiguous or the packaging portion of the machine is rendered temporarily inoperative until this conditions obtains.

Solenoids 46 are mounted upon brackets 47 carried by partition plates 24, there being a total of five solenoids, one corresponding to each tier of biscuits in the package, that is, one corresponding to each packaging station. Each solenoid 46 carries a movable plunger 48 which is pivotally secured at its end to a link 49. A shaft 50 is disposed transversely between adjacent partition plates 24, each shaft carrying a bell crank lever 51. One arm 52 of each bell crank lever is pivotally connected to each link 49. Each bell crank lever is keyed to each shaft 50 whereby movement of the bell crank lever results in movement of the associated shaft. Each shaft 50 carries three spaced hubs 53 which are keyed to the associated shaft and each hub carries a step bar 54 which terminates in an offset stop finger 55. The respective stop fingers 55 are normally disposed in the path of travel of the endmost articles upon platforms 37 whereby the columns of articles 45 are temporarily prevented from moving forwardly. A coil spring 56 is anchored at one end upon arm 52 of each bell crank lever 51 and at its opposite end upon the adjacent partition plate whereby the bell crank levers are resiliently urged in a clockwise direction, as viewed in Fig. 4. The opposed arm 57 of each bell crank lever 51 carries an adjusting screw 58 at its end which cooperates with a stop 59 carried upon the adjacent partition plate 24. By this arrangement the clockwise movement of the bell crank levers may be adjustably limited, thereby limiting the clockwise movement of the stop fingers 55.

A housing 60 is supported on top of the partition plates 24, and extends across all the groups of belts. A plurality of micro-switches 61 are positioned in said housing, one micro-switch being provided for each belt 16. Each strip 39 is provided with an elongated slot 62 and a feeler arm 63 extends through each slot. Each feeler arm 63 is connected mechanically at one end to each micro-switch 61, an intermediate portion of each arm being curved or arced and being adapted to ride upon the tops of at least two adjacent articles or biscuits at some time during their travel upon belts 16.

As will be hereinafter more fully described when the timing of the machine is explained, all of the micro-switches 61 are connected in series and when all of the arms 63 are in the position shown in full lines in Fig. 4 the series circuit comprising the switches is closed. However, if the biscuits passing beneath the curved

portion of the feeler arm 63 are not in substantially contiguous relationship, the arm in question will drop to the broken line position and the switch in question will be opened. It can readily be seen that if any one of the arms 63 moves to a dotted line position, that is, if there is less than the requisite number of biscuits on any of the belts, the series circuit including the micro-switches 61 will be opened. With the opening of the micro-switch circuit the solenoid 46 and the subsequent mechanism, to be hereinafter described will be rendered inoperative, and will remain inoperative until the micro-switch circuit is closed. Motor 11 is not included in the micro-switch circuit and, hence, belts 16 will continue to move even though the subsequent apparatus is rendered inoperative. Accordingly, if the deficiency of biscuits upon belts 16 is temporary, with the arrival of additional biscuits the micro-switch circuit will be closed and the machine will resume operation.

As has been hereinbefore described, the stop fingers 55 are adapted to restrain forward movement of the biscuits until the obstructing gates 54 are raised by the energization of the solenoids 46. As will be hereinafter described, for optimum operation of the machine a column of biscuits accumulates upon end belt 16, the biscuits in each column being in end-abutting relationship. Accordingly, the biscuit at the end of the upper pass of each belt 16 is moved onto the platform 37 by the force of the column of biscuits, the biscuits moving from the conveyor belts onto the platforms 37 until the endmost biscuit of each column is stopped by the respective stop finger 55. In accordance with the timing of the machine, the solenoids 46 are periodically energized thereby swinging gates 54 in a counterclockwise direction, as viewed in Fig. 4, thereby raising the stop fingers 55 and permitting the endmost biscuits upon platforms 37 to be discharged forwardly by the urging of the biscuit columns behind each of the endmost biscuits. The period of energization of the solenoids 46 is such that one transverse row of biscuits across the machine is permitted to be discharged from the platforms 37 at one time and one of the factors which controls this operation is the velocity of belt 16. The velocity of the belt 16 is such that one biscuit will be pushed from each of the platforms 37 during the cycle time allotted for the lift, dwell and return of stop 54 for one cycle. When the solenoids are deenergized, through the agency of springs 56 the stop fingers 55 prevent the next biscuits in the columns from moving forwardly off platform 37.

The transverse row of biscuits released by the gates 54 are pushed onto a plurality of endless conveyor belts 64 which are trained around rolls 65 and 66. Each belt 64 is in alignment with each belt 16, the belts 64 being grouped in threes, there being five such groups. At the forward ends of the upper passes of the belts 64 a stationary platform 67 is positioned, being carried by angle iron 68. By this means the five groups, three biscuits to the group, are fed into five packaging stations 69, 70, 71, 72 and 73.

A shaft 74 is carried by the partition plates 24, said shaft extending entirely across the machine. An arm 75 is rigidly mounted upon an end of said shaft, said arm being pivotally connected at its end to a curved connecting member 76. The connecting member 76 carries a rod 77 which is threadedly engaged with a sleeve 78. At the opposite end of the sleeve 78 a rod 79 is threadedly

positioned, said rod being carried by joint member 80. A piston rod 81 is connected to the joint member 80, said piston rod being carried by a piston (not shown) which operates in hydraulic cylinder 82, said cylinder being mounted upon a portion of the frame of the machine. The arrangement is such that reciprocating motion of the piston rod 81 results in a rocking motion of shaft 74.

A plurality of arms 83 are rigidly connected to the shaft 74 and are adapted to move with said shaft when the latter is rocked. There are five arms 83, one for each of the packaging stations 69 to 73 inclusive. A shaft 84 is carried between adjacent partition plates 24, there being five such shafts. An arm 85 is rigidly mounted upon each of said shafts and at the end of each arm a link 86 functions to pivotally connect the ends of the arms 85 and 83. The arrangement is such that when shaft 74 is rocked all of the shafts 84 are rocked throughout substantially the same angle.

A pair of arms 87 are rigidly mounted at their upper ends upon each shaft 84, the arms 87 being disposed on opposite sides of the arm 85 upon each shaft 84. A pusher member 88 carries spaced lugs 89 upon its upper surface and the ends of arms 87 are pivotally connected to said lugs. Each pusher member 88 carries an additional pair of lugs 90 which are pivotally connected to the lower ends of a pair of arms 91. The upper ends of each pair of arms 91 are rigidly carried upon a shaft 92 which in turn are carried between adjacent partition plates 24.

The arrangement is such that when piston rod 81 is reciprocated, shaft 74 which extends across the machine is rocked thereby rocking each of the arms 83. The arms 83 in turn rock the arms 85 thereby rocking each of the shafts 84. The rocking movement of each of the shafts 84 results in an arcuate movement of each of the pusher members 88. By virtue, however, of the suspension of the pusher members 88, said pusher members, throughout their swinging movement, move substantially parallel to the belts 64.

At the forward end of each pusher member 88 a pusher plate 93 extends downwardly. Each pusher plate carries a pair of cantilever wires 94, the purpose of which will be hereinafter more fully described. In addition, the forward portion of each of the pusher plates 93 carries a resilient pad 95 which may conveniently take the form of sponge rubber, soft felt or the like.

In the operation of the machine the solenoids 46 when energized swing the gates 54 thereby releasing a transverse row of biscuits 45 onto the upper passes of the belts 64. As has been hereinbefore described, but one biscuit is released from each column of biscuits. The transverse row of biscuits discharged to the upper passes of the belts 64 are carried forwardly to the platforms 67. During the movement of the biscuits upon the belts 64 the shaft 74 is so rocked as to move the pusher members 88 to their extreme clockwise positions, as illustrated in Fig. 5. When the pusher members are in this position, the pusher plates 93 are raised above the path of travel of the biscuits upon the belts 64. When the biscuits carried by the belts 64 come to rest upon the platform 67, the shaft 74 is rocked so as to move the pusher members 88 in a counterclockwise direction, as viewed in Fig. 4. As the pusher members 88 swing in a counterclockwise direction the pusher plates 93 carried thereby move into contiguous relationship with the rear ends of the biscuits carried upon the platform 75

67 and as a result thereof said biscuits are moved forwardly off of the platform 67. The arrangement is such that after the row of biscuits is pushed forwardly by the pusher members 88 another row of biscuits is moved by the conveyor belts 64 to be positioned upon the platform 67.

The frame member 26 is of channel construction and is disposed transversely with respect to the direction of travel of the belts 16 and 64. A similar channel frame member 96 is also disposed transverse to the direction of travel of the belts and is positioned in substantially parallel spaced relationship with respect to the frame member 26. The frame members 26 and 96 are secured together in appropriate spaced relationship by means of spacer rods 97.

A pair of shafts 98 and 99 are journaled in suitable bearings carried by the frame members 26 and 96, said shafts being disposed transversely

20 with respect to the frame members and in spaced parallel relationship with respect to each other. Two pair of sprocket wheels 100 and 101 are mounted respectively upon the shafts 98 and 99, the sprocket wheels constituting each pair being disposed in spaced relationship to each other. Sprocket chains 102 and 103 are trained around each pair of sprocket wheels 100 and 101 whereby the sprocket wheels are all moved in unison.

25 A pair of frame members 104—104 (Figs. 4, 7 and 8) are carried by the rods 97, said frame members being disposed in spaced parallel relationship with respect to each other. The sprocket wheels 100 and 101 and the chains 102 and 103 operate between the spaced plates 104.

30 Carried upon the upper and lower edges of each of the plates 104—104 are guide strips 105 which are secured to the respective frame members 104—104 by means of screws 106 or the like. A pair of guide blocks 107 are carried by each of the plates 104—104, being secured thereto by means of screws 108 or the like. The guide strips 105 and the guide blocks 107 define guideways 109 in the opposite plates 104—104, said guideways being positioned adjacent the upper and lower edges of the plates 104—104 and being co-extensive in length with said plates.

35 A plurality of form supports 110 are secured in spaced relationship to each other upon the sprocket chains 102 and 103. Each of the form supports 110 carries two pair of rollers 111 which are adapted to move in the guideways 109. It can readily be seen that when the sprocket chains 102 and 103 are moved the form supports 110 move in unison therewith, said supports being guided by rollers 111 which travel in the guideways 109.

40 A form bracket 112 is carried by each of the form supports 110, each of said brackets supporting a form 113. Each form 113 defines generally a volume which resembles the volume of the carton in which the articles are to be packaged. Each form comprises side walls 114, a rear wall 115 which extends only partially throughout the length of the side walls and an apertured front wall 116. The top of the form is open. In the operation of the device the movement of the chains 102 and 103 results in movement of the forms 113, said forms moving transversely adjacent the platform 67 from which the articles, shredded wheat biscuits, are delivered forwardly.

45 A track 117 is secured to the inner face of the frame member 96 at its upper portion. The track 117, as can readily be seen in Fig. 7, is straight throughout portions thereof; is inclined throughout portions thereof and is curved

throughout other portions thereof. The track 117 is substantially endless with the exception of one relatively short break therein.

Each form 113 carries a platform 118 which in turn is mounted upon a plate 119, the plate being disposed adjacent, and substantially parallel to, the front wall 116 of the form. A block 120 is carried upon each plate 119 and terminates in a stub shaft 121 which carries a roller 122. The roller 122 is adapted to be positioned in track 117 and during movement of the chains 102 and 103 the roller 122, following the contour of the track 117 moves the platform 118 of each form 113 longitudinally with respect to the form. As will be hereinafter more fully described, the platforms 118 in the various forms 113, when said forms are moved adjacent the packaging stations 69 to 73 inclusive function as movable bottoms for the forms 113. The motion of the chains 102 and 103 is intermittent so that a form 113 dwells adjacent a packaging station for a predetermined period of time before it moves therefrom. It will be noted that the track 117 adjacent the packaging stations 69 to 73 inclusive is inclined. The arrangement is such that the platforms 118 in those forms 113 disposed opposite the respective packaging stations are in a vertically staggered relationship, generally conforming with the angle of inclination of the track. The angle of inclination of the track 117 adjacent the packaging stations is such, taken in conjunction with the space between adjacent forms 113 that the platforms 118 of adjacent forms opposite the packaging stations are spaced vertically from each other a distance substantially equal to the thickness of the articles to be packed.

Referring particularly to Figs. 4, 11, 12 and 13 a transverse frame member 123 is carried upon the upper portion of the channel support 96. The frame member 123 is provided with an elongated recess 124 in which a shear plate 125 is secured. The frame member 123 at its upper portion also carries platform 126.

The frame member 123 comprises a casting which has two opposite end portions 127 (Fig. 11) which carry end walls 128. A plate 129 is secured to each of the end walls 128 by means of spacer screws 130. Each of the plates 129 carries a bearing 131 in which a shaft 132 is journaled at its opposite ends. A spur gear 133 is rigidly secured to shaft 132 adjacent one of the bearings 131 and said shaft carries a plurality of spaced rolls 134 intermediate its length. The rolls 134 are provided with corrugated surface 135, the function of which will be hereinafter more fully described. The rolls 134 are separated from each other throughout the length of the shaft 132 by spacer members 136.

A stub shaft 137 is mounted upon one plate 129, namely that plate to which spur gear 133 is adjacent. A pawl plate 138 is carried by the stub shaft 137 and is freely movable relative to said shaft. A ratchet wheel 139 is loosely mounted upon the shaft 137 and is disposed adjacent the pawl plate 138. A pair of spaced pawls 140 and 141 are pivotally mounted, as at 142 and 143 respectively (Fig. 12) upon the pawl plate 138. Blade springs 144 and 145 bear respectively upon one end of each of the pawls 140 and 141 whereby the noses 146 and 147 of said pawls respectively are urged toward the ratchet teeth of the ratchet wheel 139. A spur gear 148 is also loosely mounted upon the stub shaft 137 and meshes with spur gear 133 mounted upon shaft 132.

A bracket 149 is secured by means of screws or

the like 150 to the frame member 96, said bracket at its opposite end supporting a fluid pressure cylinder 151. Piston rod 152 which operates in the cylinder 151 is connected by means of connecting rod 153 to pawl plate 138, the connection between the connecting rod 153 and the pawl plate being pivotal. The arrangement is such that when piston rod 152 moves upwardly it rocks pawl plate 138 in a counterclockwise direction, as viewed in Fig. 12, thereby rocking the pawls 140 and 141 relative to the ratchet wheel 139. The ratchet wheel 139 although loosely mounted upon stub shaft 137 is prevented from moving due to the engagement of the spur gears 148 and 133, there being sufficient friction in the movement of shaft 132 to prevent rotation of the ratchet wheel 139 when the pawls move counterclockwise. When the piston rod 152 moves downwardly the pawl plate 138 is rocked in a clockwise direction, as viewed in Fig. 12, and one or the other of the noses 146 or 147 of the respective pawls engages in one of the teeth of the ratchet wheel 139. Such engagement causes the ratchet wheel to be rocked in timed relationship with the pawl plate and hence spur gear 148 is rotated thereby rotating spur gear 133 and shaft 132. It will be noted that the shaft 132 is rocked in a counter-clockwise direction, as viewed in Fig. 12.

As will be hereinafter more fully described, the mechanism described is employed to feed to each of the packaging stations a cardboard separator which is interposed between the layers of biscuits in the forms. Each of the rolls 134 is adapted to feed one separator forwardly. Accordingly, there are five rolls 134 mounted in spaced relationship upon shaft 132.

Associated with each roll 134 is a guide plate 154 having upwardly extending guide flanges 155. The guide plates 154 are in alignment with the rolls 134 and are inclined in a direction substantially tangent to said rolls. A continuous fibrous corrugated member 156 is adapted to move upwardly along each guide plate 154, the corrugated member 156 having a flat fibrous liner 157 and an adhesively united corrugated fibrous member 158. The corrugations in the surfaces of the rolls 134 are such as to conform with the corrugations 158 and in order to feed the corrugated members 156 upwardly and forwardly the corrugations 158 of each corrugated member are brought into registration with the corrugations 135 in the rolls 134. Accordingly, when the rolls 134 are rocked the corrugated members 156 are fed forwardly upon the platform 126 until a portion of the corrugated member overlies the edge of the shear plate 125.

A top plate 159 is mounted upon each of the castings 127 adjacent the end plates 128. A bearing 160 is mounted upon each of the top plates and functions to support a shaft 161. Throughout the length of the shaft 161 a plurality of sleeves 162 are mounted in embracing relationship with respect to said shaft, said sleeves being loosely mounted upon the shaft. Adjacent the opposite ends of each sleeve are arms 163 which at their outer ends are pivotally connected to lugs 164 carried upon confining plates 165. The confining plates 165 are of curved contour and are adapted to rest upon the respective corrugated members 156 as they pass over the rolls 134. The confining plates 165 extend downwardly in substantially parallel relationship to the inclined guide plates 154 whereby the corrugated members 156 are confined beneath the confining plates 165 as said corrugated members

leave the guide plates 154 and travel over the respective rolls 134. In view of the fact that the sleeves 162 are loosely mounted upon shaft 161 the confining plates 165 merely rest by gravity upon the upper portion of the respective corrugated members during their passage over the rolls 134. To prevent undue buckling of the corrugated member between the rolls 134 and the shear plate 125 a plurality of horizontal guides 166 are mounted in spaced relationship over platform 126.

Mounted at each end of the transverse frame member 128 is an upwardly extending guide rod 167. A standard 168 supports each guide rod 167 at its upper end. A shearing frame 169 is slidably mounted at each of its ends upon the opposite guide rods 167, the shearing frame being adapted for vertical slidable movement upon said rods. A shaft 170 is mounted upon one of the standards 168 and extends outwardly therefrom. At the end of the shaft 170 an arm 171 is rigidly mounted, the end of said arm being pivotally connected to connecting rod 172 which in turn is pivotally connected to a piston rod 173 which operates in fluid pressure cylinder 174 carried upon the frame member 96 by means of brackets 175. At the opposite end of shaft 170 on the opposite side of standard 168 from arm 171 an arm 176 is carried, said arm being rigidly connected to shaft 170. A lug 177 is mounted upon the shear frame 169 and a link 178 pivotally connects the end of arm 176 to lug 177. The arrangement is such, that when piston rod 173 is reciprocated within the cylinder 174 shaft 170 is rocked thereby slidably moving the shear frame 169 upwardly and downwardly along the guide rods 167.

A plurality of shearing blades 179 are carried upon the lower portion of the shear frame 169, said blades being secured to the shear frame by means of pins 181 which pass loosely through apertures in the blades, said pins being embraced by coil springs 182 to maintain each of the shearing blades 179 in firm resilient contact with the shear frame 169. The shearing blades 179 during reciprocating motion of the shear frame 169 cooperate with the shear blades 125 carried upon the frame 123. Transversely, the blades 179 are spaced from each other so as to shear the corrugated members 156 which are moved forwardly over the upper surface of the shear plate 125.

During the operation of the machine the biscuits 45 which are delivered by the belts 64 to the platforms 67 are moved from the platforms by means of the pusher members 88. During this operation a form 113 is positioned at each packaging station. It will be noted, however, that the charging stations, that is, the five pusher members 88 are offset laterally with regard to the five separator cutting stations. The form 113 which is opposite the first cutter station, that is, the endmost cutter to the right as viewed in Fig. 7, has its movable platform 118 at its uppermost position. The upper surface of the platform 118 of this form is beneath the shear plate 125. Consequently, when a length of the corrugated member 156 has been delivered forwardly by the roll 134 and the shear frame 169 has descended, a strip of the corrugated member will be cut from the member proper and will be deposited immediately upon the upper surface of the platform 118.

The form in question then moves to the left as viewed in Fig. 7. The platform 118 in moving to the next cutter station is lowered by virtue of the inclined track 117. The form stops op-

posite this cutter station which is also in alignment with the first packaging station. The pusher member 88 in this packing station moves the three biscuits 45 carried upon the platform 67 at this packaging station onto the upper surface of the platform 118. However, a separator strip was previously deposited upon the platform 118 and hence the three biscuits have a separator strip interposed between them and the upper surface of the platform 118. After the three biscuits have been charged to the form in this station the roll 134 operates to move a length of the corrugated member forwardly and a strip is sheared therefrom, the strip falling onto the upper surface of the three biscuits positioned in the form. While the strip is being deposited upon the three biscuits in the form in question a corrugated strip is deposited upon the next form rearwardly with respect to the motion of the forms, that is, the endmost form to the right shown in Fig. 7.

The form in question then moves to the next packaging station, the platform 118 descending by virtue of the inclined track 117. Three biscuits are deposited upon the separator carried upon the upper surfaces of the first three biscuits carried upon the platform. The form immediately to the right of the form in question, as viewed in Fig. 7, receives simultaneously its first tier of three biscuits. Subsequently, corrugated strips are deposited upon the second tier of biscuits in the form in question and the first tier of biscuits in the form to the right thereof and also to the upper surface of the platform 118 of the form immediately adjacent the last form mentioned.

The form in question then moves to the next packaging station and the operation is repeated until five layers or tiers of biscuits are deposited within the form and carried by the platform 118. After the operation has continued past the period when the first five forms are moved through the packaging stations, the subsequent operations are repeated. The pusher members 88 simultaneously push three biscuits to the form in the respective packaging stations. Subsequently five strips of corrugated material are deposited from the five shearing stations. This operation is a continuous operation.

In order to prevent the sheared corrugated material from buckling during and after the shear frame 169 descends a pair of spring fingers 183 carried by the pins 180 descend with each cutter blade carried by the shear frame 169. The ends of the spring fingers 183 bear upon the upper surface of the cut strip of corrugated material. Prior to that time, however, a pair of spring fingers 94 carried by each pusher member 88 move into a position above the deposited biscuits during the time that the pusher members move the biscuits into the form. Hence, when the corrugated strip is fed forwardly in overhanging relationship to the biscuits fed to the form, the fingers 94 are deposited immediately beneath the strip of corrugated material. When the shearing plate 125 descends the fingers 183 move with resilient pressure onto the upper surface of this strip. The ends of the fingers 183 and 94 are thus in contact with the strip, the fingers 183 being flexed upwardly by the strip and the fingers 94 being flexed downwardly by the strip. Accordingly, each strip is maintained in a substantially flat horizontal position whereby when the pusher members 88 move rearwardly away from the form the fingers 183 cause

the corrugated strip to be moved downwardly under the resilient pressure built up in the spring fingers. In this fashion the severed corrugated strip is prevented from buckling or canting and is deposited upon the upper surfaces of the tier of biscuits in a proper manner.

As has been hereinbefore described, the forms 113 are moved intermittently relative to the packaging stations 69-73 inclusive, said forms being carried by the sprocket chains 102 and 103. The sprocket chains in turn are driven by the sprocket wheels 100 and 101 mounted respectively on shafts 98 and 99. The shaft 99 is the drive shaft and the drive for moving the forms in intermittent fashion will be hereinafter more fully described.

Referring particularly to Figs. 9 and 10, it will be noted that shaft 98 is journaled in frame 26. A spur gear 185 is mounted upon shaft 98 and is adapted to mesh with a spur gear 186 mounted upon shaft 187 positioned immediately beneath shaft 98. A ratchet wheel 188 is freely mounted upon shaft 187 and is rigidly secured to spur gear 186. The ratchet wheel 188 is provided with ratchet teeth 189 defined on one side by shoulder 190 and on the opposite side by the tapered surface 191. A pawl plate 192 is freely mounted upon shaft 187 and carries a pawl 193 pivotally secured to the pawl plate 192 as at 194 in Fig. 10. A coil spring 195 is anchored at one end upon the pawl 193 and at the opposite end upon pin 196 which is carried by the pawl plate 192, said spring functioning to urge the pawl 193 toward the ratchet teeth.

A link 197 is pivotally mounted at one end as at 198 in Fig. 10 to the pawl plate 192. The opposite end of the link 197 is provided with an elongated slot 199 which is adapted to engage with a pin 200 carried upon an arm 201. The arm 201 is pivotally connected as at 202 in Fig. 10 to lug 203 carried upon a portion of the frame 26.

Pawl plate 192 is pivotally connected as at 204 in Fig. 10 to a connecting rod 205. The connecting rod 205 at its opposite end is pivotally connected as at 206 to clevis 207 which is carried upon the end of piston rod 208. Piston rod 208 operates in fluid pressure cylinder 209 which is carried by means of brackets 210, only one of which is shown, which in turn secures the cylinder 209 in fixed position upon the frame 26.

At the end of shaft 98 upon the opposite side of frame 26 from the sprocket wheels a drum 211 is rigidly carried. A brake band 212 carrying a brake lining 213 embraces the face of the drum 211. The brake band 212 is pivotally anchored as at 214 in Fig. 10 to a portion of the frame 26 and an arm 215 is pivotally secured at the point of anchorage of the brake band 212. Intermediate the length of arm 215 the opposite end of the brake band 212 is pivotally secured as at 216 in Fig. 10. An adjustable link 217 is pivotally connected at one end to the free end of the arm 215 and at the opposite end is pivotally secured to one end of lever 218. The lever 218 is pivotally mounted on a stub shaft 219 carried upon frame 26. A fluid pressure cylinder 220 is carried by means of brackets 221 upon a portion of frame 26 and a piston rod 222 is operatively positioned within the cylinder 220. The end of arm of lever 218 is constructed in the form of a fork 223 which embraces a portion of piston rod 222, nuts 224 functioning to maintain the fork 223 in operative relationship with respect to the piston rod 222.

The operation of the intermittent drive here-

inabove described is as follows: The introduction of fluid pressure into one or the other end of cylinder 209 causes piston rod 208 to reciprocate within the cylinder. This motion is transmitted to the pawl plate 192 and results in a rocking motion of the pawl plate about shaft 187. When the pawl plate 192 is rocked in a counterclockwise direction, as viewed in Fig. 10, the pawl 193 rides over the tapered face 191 of one of the ratchet teeth and eventually positions itself with its operative end adjacent a shoulder 190 of said ratchet tooth. Simultaneously the link 197 moves upwardly, as viewed in Fig. 10, the pin 200 relatively moving within the slot 199 until the lower end of said slot is encountered at which time the arm 201 is rocked in a clockwise direction, as viewed in Fig. 10, about the pivot 202. In this fashion the end of arm 201 is disengaged from a tapered side of one of the ratchet teeth.

During this operation, that is, when the pawl plate is rocked in a counterclockwise direction the piston rod 222 so moves as to apply the brake to the drum 211. In other words, the piston rod 222 moves inwardly relative to the cylinder 220. Accordingly, during the period that the pawl plate 192 rocks in a counterclockwise direction the shaft 98 is maintained stationary by the brake. Obviously, shaft 98 is maintained stationary during this period which results in the forms being stationary and a predetermined number thereof being disposed adjacent the packaging stations.

Thereafter piston rod 208 moves to the left, as viewed in Fig. 10, thereby rocking pawl plate 192 in a clockwise direction. In view of the fact that the operative end of pawl 193 is in engagement with a shoulder 190 of a ratchet tooth, the ratchet wheel 188 is also rocked in a clockwise direction. This rocking operation is imparted to spur gear 186 which in turn rotates spur gear 185 and rotates shaft 98. At the inception of the clockwise movement of the pawl plate 192 the brake upon shaft 98 is released by the appropriate movement of the piston rod 222. As the clockwise movement of the pawl plate 192 takes place, link 197 moves downwardly as viewed in Fig. 10 until the pin 200 carried upon the arm 201 engages the upper end of the slot 199 at which time the arm 201 is rocked in a counterclockwise direction about the pivot 202 until the tapered end of the arm 201 contacts the tapered face 191 of the adjacent ratchet tooth. This limits the clockwise movement of the pawl plate 192 and hence properly locates predetermined forms 113 in the adjacent packaging stations. In this fashion an intermittent movement is imparted to the sprocket chains which in turn periodically move the forms from one packaging station to the next packaging station, also causing the forms adjacent the packaging stations to dwell at the packaging stations for a predetermined period of time necessary to charge the forms with the biscuits and properly position the corrugated strips within the forms.

Referring to Figs. 14, 15 and 16, the timing mechanism for the machine is illustrated. The timing mechanism designated generally by the reference numeral 225, is carried within a housing comprising a base 226, end walls 227-227 and removable cover 228 comprising the side walls and top of the housing. The mechanism comprises essentially a sequence-timer shaft 229 journaled in suitable bearings supported by

226. The shaft 229 is driven by a fluid motor 231 which, in turn, receives fluid under pressure from a fluid pump 232 (Fig. 3), the latter being driven by an electric motor 232'. The fluid motor 231 drives the sequence timer shaft 229 through a conventional gear reducer 233 coupled to the motor 231 by means of coupling 233'. A solenoid operated valve (not shown in Figs. 14, 15 or 16, the solenoid, however, being shown diagrammatically at 234 in Fig. 17) controls the flow of fluid from pump 232 to fluid motor 231, the arrangement being such that, when the valve is open the shaft 229 rotates and when closed the shaft 229 is stopped.

Brackets 235 are carried upon the inner face of each of the end walls 227—227, said brackets being adapted to support a platform 236 which is positioned above, and disposed parallel to, the sequence-timer shaft 229. A plurality of fluid operating valves 237, 238, 239, 240 and 241 are mounted upon the platform 236, said valves being carried in spaced relationship along the length of the platform. The valves 237 to 241 inclusive are all similar and are of the conventional four-way spool type, the control element of each valve being operated by rod 242 which projects from each valve. Each of the valves 237 to 241 inclusive has a connection to a source of fluid under pressure (not shown); a return line connection to a fluid reservoir (not shown) and connections to each end of cylinders 82, 151, 174, 209 and 220, respectively. When the rod or stem 242 of each of the valves is in its in-position, the pressure source is connected to one end of a respective operating cylinder while the other end is vented to the return line. When the stem is in its outermost position, these connections are reversed.

A plurality of pairs of cams 245 are mounted upon the timer shaft 229, one pair of cams being disposed adjacent each of the valves 237 to 241 inclusive. Each cam pair 245 comprises cams 246 and 247. A bracket 268 is carried upon platform 236 adjacent each cam pair 245 and a T-shaped lever 248 is pivoted at the juncture of the T-arms to each bracket. One arm 249 of each of the levers 248 is pivotally connected to a link 250 which latter is pivotally connected to each of the stems 242 of the valves 237 to 241 inclusive. The opposite arm 251 of each of the levers carries a cam roller 252 which cooperates with each of the cams 247. The transverse arm 253 of each of the levers carries a cam roller 254 which cooperates with each of the cams 246. The arrangement is such that in conjunction with each valve 237 to 241 inclusive, each cam 246 functions through the transverse arm 253 to move the respective stem to its outermost position and each cam 247 through the agency of an arm 251 functions to move the respective stem to its innermost position.

Valve 237 is associated with cylinder 32 and controls the release of a transverse row of biscuits from the platform 31. Valve 238, is associated with cylinder 151 and controls the operation of said cylinder, which, in turn, controls the forward feed of the spacers 156. Valve 239 similarly controls the operation of cylinder 174 for moving the shear frame 169 to cut the spacers. Valve 240 controls the operation of cylinder 209 for intermittently driving the shaft 98 which, in turn, moves the package forms, and valve 241 controls the operation of cylinder 220, which, in turn, manipulates the brake for stopping shaft 98 and the associated form-moving mechanism.

A shaft 255 is mounted upon brackets 256 car-

ried by platform 236 and a lever 257 is mounted upon said shaft and is rotatable relative thereto. One end of lever 257 carries a cam-follower roller 258 which is adapted to ride upon the periphery of cam 259 which, in turn, is mounted upon timer shaft 229 and rotates therewith. A coil spring 260 connected to an arm 261 of lever 257 is anchored upon the platform 236 at its opposite end and functions to maintain roller 258 in contact with cam 259. A bracket 262 is carried upon lever 257 and carries a mercury switch 263 comprising a portion of the electrical circuit shown in Fig. 17, to be hereinafter more fully described. As will be brought out hereinafter switch 263 is normally closed and is periodically opened once during each rotation of shaft 229 by the peak of cam 259.

Referring particularly to Fig. 17, 264 indicates a source of electric current. A conductor 265 connects one side of the line to a plurality of micro-switches 61 all of which are connected in series. The circuit containing the micro-switches connects through solenoid 234 to conductor 266, which, in turn, connects to the opposite side of the line. As has been hereinbefore described solenoid 234 operates the control valve which governs the flow of fluid from pump 232 to fluid motor 231. Mercury switch 263, carried by cam-operated lever 257 is connected in parallel with the micro-switches 61, that is, the micro-switches connected in series with each other are connected in parallel with the mercury switch 263 and the parallel circuit so formed is connected in series with solenoid 234.

As has been hereinbefore described, each micro-switch 61 is closed when its respective arm 63 is in upraised position, being maintained in this position when a column of articles are in end abutting relationship upon belt 16 (Fig. 4). As has also been hereinbefore described, mercury switch 263 is normally closed, but is periodically opened once per revolution of timer shaft 229. Hence, when all of the micro-switches 61 are closed, the circuit to the solenoid 234 remains closed regardless of the periodic opening of the mercury switch and, hence, shaft 229 continues to rotate since the valve controlled by solenoid 234 remains open and fluid is delivered to motor 231. Whenever the arm 63 of any one of the micro-switches 61 drops to the dotted line position (Fig. 4) due to a deficiency of biscuits upon a belt 16, the corresponding switch 61 opens. However, the circuit to solenoid 234 remains closed for a period of time due to the fact that mercury switch 263 is closed. Hence, shaft 229 continues to rotate until switch 263 is opened. If, when mercury switch 263 opens, the micro-switch 61, in question, is still open, that is, the contiguous relationship of the biscuits upon belt 16 has not been reestablished, the circuit to solenoid 234 opens with the opening of the mercury switch and shaft 229 stops. Hence, all operations of the machine stop except the movement of belts 16 which continue to move thereby tending to reestablish the column of articles upon the belt in question and close the respective micro-switch. When this occurs, solenoid 234 is again energized and the valve between pump 232 and motor 231 is opened and shaft 229 is again rotated.

In the optimum condition for operation of the machine proper relative to the conveyors 16, an accumulation or column of biscuits extending from each finger 55 to about the vicinity of the arm 63, but not appreciably farther back on the conveyor, is contemplated. This condition is

obtained in the following manner: The speed of the sequence timer shaft 229 is maintained above the rate of supply of biscuits. Obviously this condition would operate to progressively deplete the biscuit supply on each belt, that is, the columns of biscuits on the belts would be progressively reduced in length. However, whenever the column length is reduced to a point in advance of the arm 63, a controlled waiting period is introduced during which the length of the column on each belt is extended to the minimum predetermined by the position of the arm 63.

A shaft 267 is mounted upon spaced supporting brackets 263 which, in turn, are carried upon the platform 236. A cam follower lever 269 is rotatably positioned upon the shaft 267 and carries at its end a cam follower roller 270 which is maintained in operative position upon the periphery of cam 271 mounted upon the timer shaft 229. The roller 270 is maintained in operative position upon the cam surface by means of a coil spring, not shown, similar to coil spring 260 hereinbefore described in conjunction with the lever 257. A bracket 272 is mounted upon the cam follower lever 269 and carries a mercury switch 273. As will be hereinafter more fully described, the mercury switch 273 is normally open and periodically closes during the rotation of the cam 271, the switch closing once during each rotation of the cam.

A cam lever 274 is also rotatably mounted upon shaft 267, said cam lever carrying a cam follower roll 275 which cooperates with the periphery of cam 276 mounted upon the timer shaft 229. A coil spring (not shown) functions to maintain the cam follower roller 275 in operative contact with the surface of the cam 276. A bracket 277 is mounted upon the lever 274, said bracket carrying a mercury switch 278.

Referring particularly to Fig. 17, it will be noted that the mercury switch 278 is connected by conductor 279 to one side of the source of current 264. A conductor 280 connects the opposite side of the mercury switch 278 to one side of five solenoids 46. The opposite side of said solenoids are connected by means of conductor 281 to the opposite side of the line.

As has been hereinbefore described the solenoids 46 control the operation of the biscuit stops 54, the arrangement being such that when the solenoids are operated the fingers 55 carried by the stops 54 raise and permit a transverse row of biscuits to move from platform 37 to the belts 64. Accordingly, the mercury switch 278 is normally open, that is, the solenoids 46 are normally deenergized and the stops 54 are maintained in biscuit restraining position by means of the springs 56. As the shaft 229 rotates, however, cam 276 functions to rock the cam follower lever 269 and thereby close the mercury switch 278 completing the circuit to the solenoids 46. This operation occurs once during each complete revolution of cam 276.

As has been hereinbefore described, a tier of three biscuits is deposited in the forms at each packaging station, said tier having interposed separators. When the forms leave the last packaging station 73, the forms carry five tiers of biscuits. The tiers thus carried in the forms are inverted relative to the position they are intended to occupy in the carton. Hence, when the biscuit-loaded forms leave the station 73, a package or carton 282 in inverted position, its top being open and its bottom closed, is manually telescopically slid over the form 113 carrying the biscuit tiers until the bottom of the carton rests

upon the then uppermost tier of biscuits, as clearly shown in Fig. 7.

The forms embraced by the packages then continue their travel as the sprocket chains 110 and 112 move around sprocket wheels 100, the movable platform 118 being maintained at a constant position relative to the form by the curved track 117. A semi-circular guide housing 383 circumscribes the curved path of the forms and prevents accidental removal of the cartons from the forms. After the forms pass substantially the horizontal position in being carried over sprocket wheels 100, one rail of the track 117 is discontinued, the roller 122 then being guided by the remaining rail under the influence of gravity.

After passing around sprocket wheels 100, the forms are inverted with the bottoms of the cartons 282 lowermost. The rollers 122 are thereafter guided by the double track 117 which after a short horizontal travel inclines downwardly. The rollers 122 cammed by the inclined track move the platform 118 progressively downwardly thereby sliding the biscuits and cartons off of the forms.

An endless conveyor 284, trained around end rolls 285, idler roller 286 and tightener roll 287 carried by a swingable arm 288, is positioned beneath the track 117 and when the loaded cartons are removed from the forms they are deposited right-side-up upon the conveyor whereby they may be delivered for inspection and to suitable mechanism (not shown) for sealing the top flaps. A pair of guide rails 289 and 290 are disposed upon each side of the path of travel of the cartons and parallel said path from adjacent the lower arc of their travel around the sprocket wheels 100 to the end of the conveyor 284. Said rails prevent lateral displacement of the loaded cartons.

To facilitate the positioning of the cartons over the forms and tiers of biscuits after they leave the station 73, a jogging plate 291 makes contact with the biscuits and separators to dispose them in a position adjacent the wall 116 of the form 113. The jogging device comprises a solenoid 292 of plunger 293 actuated thereby.

Referring particularly to Fig. 17, it will be seen that solenoid 292 is connected across the source of current 265 through mercury switch 273 carried by the cam follower lever 269. The switch 273 is normally closed, but is opened once during each revolution of timer shaft 229 at which time a coil spring 293' functions to actuate the jogging plate 291, moving into contact with the biscuits and separators in the form 113.

It can readily be seen that a complete cycle of the machine is measured by one complete revolution of the sequence timer shaft 229. During one complete revolution of said shaft cam 276 rocks the cam follower lever 274 to close the normally open mercury switch 278 thereby energizing the solenoids 46 and permitting the release of one transverse row of biscuits from the platform 37. During one revolution of the shaft 229 the piston associated with the valve 237 causes one complete reciprocation of the piston rod 81 associated with the cylinder 82 and hence the pusher mechanism moves forwardly to discharge the biscuits from the platform 67 into the forms 113. On the reverse motion of the piston rod 81 the pusher mechanism swings backwardly and upwardly away from the platform 67 to permit the forward delivery of another transverse row of biscuits from the belts 64. With one complete revolution of the shaft 229 the

piston associated with the valve 238 causes piston rod 152 operating in cylinder 151 to make one complete cycle to feed a portion of the separator web forwardly and then to return to feeding position. With one complete revolution of the shaft 229 the piston associated with valve 239 causes the shear frame 169 to descend and raise thereby severing a separator strip from the web which is fed forwardly. With one revolution of shaft 229 the piston associated with valve 240 operates the piston rod 208 to rock the pawl plate 192 to rotate shaft 98. The rotation of the shaft 98 moves the forms from one packaging station to the next packaging station. With one complete revolution of the shaft 229 the piston rod 222 operating in cylinder 220 applies and releases the brake upon shaft 98 to hold the forms at the packaging station while the packaging operation is being performed, the brake being released to permit the stepwise movement of the forms from one station to the next. With one revolution of the shaft 229 the solenoid 292 is deenergized by the opening of the normally closed mercury switch 273 carried upon the cam follower arm 269. With one revolution of the shaft 229 the mercury switch 263 carried upon the cam follower arm 257 is opened, said mercury switch being normally closed. The opening of the mercury switch 263 once during each revolution of the shaft 229 permits the micro-switches 61 to control the operation of solenoid 234. As has been hereinbefore described, if one of the micro-switches is opened, the opening of the mercury switch 263 causes solenoid 234 to become deenergized thereby opening the valve between the pump 232 and the fluid pressure motor 236 stopping the operation of shaft 229.

It is to be understood that the machine embodying the present invention is not limited in its use to the packaging of shredded wheat biscuits since it will find use wherever it is desired to pack individual articles in a carton particularly where the articles are packed in tiers. It is also to be understood that the invention is not limited to a machine for packaging five tiers of articles, three articles to a tier, in a carton, since as many tiers as desired may be packed with as many articles as desired constituting each tier. With regard to the location of the timing mechanism shown in Figs. 14, 15 and 16 relative to the machine proper, it may be mounted at any convenient place since it can be conveniently connected to the active portions of the machine by pipes and electrical conductors.

I claim as my invention:

1. A packaging machine for packaging an article in a carton which comprises an endless conveyor for carrying an article forwardly in a predetermined direction, means for moving said conveyor, gate means disposed adjacent the delivery end of said conveyor for releasing said article carried forwardly from said conveyor, a packaging station in alignment with said conveyor, reciprocating pusher means for moving said released articles in a direction aligned with said conveyor into said station, a package form positioned in said station to receive the article moved into said station, and means for moving said package form from said station transversely to the path of movement of the article into said station, and means for transferring said article from said package form to a carton.

2. A packaging machine for packaging an article in a carton which comprises an endless conveyor for carrying an article forwardly, means

for continuously moving said conveyor, gate means disposed adjacent the delivery end of said conveyor for releasing an article carried forwardly upon said conveyor, a second endless conveyor for receiving said released article and for carrying the same forwardly, a packaging station, pusher means for moving said article from said second conveyor into said station, a package form positioned in said station to receive the article moved into said station, and means for moving said package form from said station transversely to the path of movement of the article into said station, and means for transferring said article from said package form to a carton.

3. A packaging machine for packaging articles in a carton which comprises a plurality of parallel positioned endless conveyors for carrying articles forwardly, means for continuously moving said conveyors, gate means disposed adjacent the delivery end of said conveyors for periodically releasing articles carried forwardly one by one simultaneously from all said conveyors, a plurality of packaging stations, pusher means for periodically sliding each of said articles into each of said stations, a plurality of package forms one in each station, means for intermittently moving said package forms into and out of said stations, said package forms while in said stations being adapted to receive the articles moved into said stations, and means for transferring said articles from said package forms to cartons.

4. A packaging machine for packaging a predetermined number of articles in a predetermined positional relationship to each other in a carton which comprises a plurality of groups of parallel endless conveyors for carrying articles forwardly, means for continuously moving said conveyors, gate means disposed adjacent the delivery end of said conveyors for periodically releasing articles carried forwardly one at a time simultaneously from all said conveyors, a plurality of packaging stations, means for periodically moving said articles in groups corresponding to said conveyor groups into said stations, a transverse endless conveyor, means for intermittently moving said conveyor through said stations, package forms carried by said transverse conveyor a predetermined number of which corresponding to the number of groups being positioned in said packaging stations one form at each station each form to receive articles from one conveyor group, and means for transferring said articles from said package forms to cartons.

5. A packaging machine for packaging articles in a carton which comprises a plurality of parallel positioned endless conveyors for carrying articles forwardly, means for moving said conveyors, gate means for interpositioning between adjacent articles on said conveyor to obstruct forward movement of said articles, solenoid means to control said gate means for releasing articles carried forwardly one by one from all said conveyors, a plurality of packaging stations, means for moving said articles into said stations in timed relationship with the operation of said gates, a package form positioned in each station to receive the articles moved into said station, means for moving said package forms from said stations transversely to the path of movement of the articles into said stations, and means for transferring said articles from said package forms to cartons.

6. A packaging machine for packaging a predetermined number of articles in a predetermined positional relationship with respect to each other in a carton which comprises, a plurality of parallel endless conveyors for carrying articles forwardly, said conveyors being divided into a plurality of laterally parallel groups, gate means disposed adjacent the discharge end of said conveyors for restraining forward movement of said articles, means for periodically opening said gate means to simultaneously release one article from each conveyor, a transverse conveyor, a plurality of package forms mounted upon said transverse conveyor, means for intermittently moving said transverse conveyor and said forms in a straight line transversely to said parallel endless conveyors in timed relationship with the opening of said gate, means for disposing a package form in alignment with each group of conveyors when said transverse conveyor is stationary, and means for pushing the articles from each group released from said endless conveyors into a respective package form in timed relationship with the stopping of said forms, and means for transferring the articles from each form into a carton.

7. A packaging machine for packaging a predetermined number of articles in a predetermined positional relationship with respect to each other in a carton which comprises, a plurality of parallel endless conveyors for carrying articles forwardly, said conveyors being divided into a plurality of laterally parallel groups, gate means disposed adjacent the discharge end of said conveyors for restraining forward movement of said articles, means for periodically opening said gate means to simultaneously release one article from each conveyor, the gate opening means being equal in number to the groups, a transverse conveyor movable at right angles to said parallel endless conveyors, said transverse conveyor carrying a plurality of package forms which are fixedly mounted thereon, means for intermittently moving said transverse conveyor in timed relationship with the opening of said gate, means for disposing a package form in alignment with each group of conveyors, means for maintaining said package forms stationary in such aligned position, and means for pushing the articles from each group released from said endless conveyors into a respective package form in timed relationship with the stopping of said forms, and means for transferring the articles from each form into a carton.

8. A packaging machine for packaging a predetermined number of articles in a predetermined positional relationship with respect to each other in a carton which comprises, a plurality of parallel endless conveyors for carrying articles forwardly, said conveyors being divided into a plurality of groups, gate means disposed adjacent the discharge end of said conveyors for restraining forward movement of said articles, solenoid means for periodically opening said gate means to simultaneously release one article from each conveyor, a transverse conveyor, said transverse conveyor carrying a plurality of package forms, fluid pressure means for intermittently moving said transverse conveyor, means for timing the fluid pressure means relative to the solenoid means, means for disposing a package form in alignment with each group of conveyors when said transverse conveyor is stationary, and means for pushing the articles from each group released from said endless conveyors

into a respective package form in timed relationship with the stopping of said forms, and means for transferring the articles from each form into a carton.

5 9. A packaging machine for packaging a predetermined number of articles in a predetermined positional relationship with respect to each other in a carton which comprises, a plurality of parallel endless conveyors for carrying articles forwardly, said conveyors being divided into a plurality of laterally parallel groups, gate means disposed adjacent the discharge end of said conveyors for restraining forward movement of said articles, means for periodically opening said gate means to simultaneously release one article from each conveyor, a transverse conveyor, a plurality of package forms carried upon said transverse conveyor, means for intermittently moving said transverse conveyor, means for disposing a package form in alignment with each group of conveyors when said transverse conveyor is stationary, and means for pushing the articles from each group released from said endless conveyors into a respective package form, means for timing the gate opening means, the conveyor moving means and the pushing means relative to each other, and means for transferring the articles from each form into a carton.

10 10. A packaging machine for packaging a predetermined number of articles in a predetermined positional relationship with respect to each other in a carton which comprises, a plurality of parallel endless conveyors for carrying articles forwardly, said conveyors being divided into a plurality of laterally parallel groups, gate means disposed adjacent the discharge end of said conveyors for restraining forward movement of said articles to maintain the articles on the conveyor in substantially contiguous columnar relationship to each other, means for opening said gate means to simultaneously release one article from each conveyor, a transverse conveyor, a plurality of package forms mounted upon said transverse conveyor, means for intermittently moving said transverse conveyor in timed relationship with the opening of said gate, means for disposing a package form in alignment with each group of conveyors when said transverse conveyor is stationary, and means for pushing the articles from each group released from said endless conveyors into a respective package form in timed relationship with the stopping of said forms, and means for transferring the articles from each form into a carton.

15 11. A packaging machine for packaging a predetermined number of articles in a predetermined positional relationship with respect to each other in a carton which comprises, a plurality of parallel endless conveyors for carrying articles forwardly, said conveyors being divided into a plurality of groups, gate means disposed adjacent the discharge end of said conveyors for restraining forward movement of said articles, to maintain the articles on the conveyor in substantially contiguous columnar relationship to each other, means for periodically opening said gate means to simultaneously release one article from each conveyor, feeler means positioned adjacent each conveyor for rendering said gate opening means inoperative when the articles on a predetermined conveyor are spaced a predetermined distance from each, a transverse conveyor, a plurality of package forms mounted upon said transverse conveyor, means for intermittently moving said transverse conveyor in timed relationship with

the opening of said gate, means for disposing a package form in alignment with each group of conveyors when said transverse conveyor is stationary, and means for pushing the articles from each group released from said endless conveyors into a respective package transverse conveyor, in timed relationship with the stopping of said forms, and means for transferring the articles from each form into a carton.

12. A packaging machine for packaging a predetermined number of articles in tiers in a carton which comprises, a plurality of parallel endlessly moving conveyors for carrying articles forwardly, said conveyors being divided into a plurality of groups corresponding to the number of tiers to be packed, gate means disposed adjacent the discharge end of said conveyors for restraining forward movement of said articles, means for periodically opening said gate means to simultaneously release one article from each conveyor, a transverse conveyor, a plurality of package forms mounted upon said transverse conveyor, means for intermittently moving said transverse conveyor in timed relationship with the opening of said gate, means for disposing a package form in alignment with each group of conveyors when said transverse conveyor is stationary, means for pushing the articles from each group released from said endless conveyors into a respective package form to form a tier of articles in the form, and means for transferring the articles disposed in tiers from each form into a carton.

13. A packaging machine for packaging a predetermined number of articles in tiers in a carton which comprises, a plurality of parallel endless conveyors for carrying articles forwardly, said conveyors being divided into a plurality of groups corresponding to the number of tiers to be packed, gate means disposed adjacent the discharge end of said conveyors for restraining forward movement of said articles, means for periodically opening said gate means to simultaneously release one article from each conveyor, a transverse conveyor, a plurality of package forms mounted upon said transverse conveyor, means for intermittently moving said transverse conveyor in timed relationship with the opening of said gate, means for disposing a package form in alignment with each group of conveyors when said transverse conveyor is stationary, means for pushing the articles from each group released from said endless conveyors into a respective package form to form a tier of articles in the form, means for moving said forms into alignment with consecutive groups to receive a plurality of superimposed tiers of articles, and means for transferring the superimposed tiers of articles from each form into a carton.

14. A packaging machine for packaging a predetermined number of articles in tiers in a carton which comprises, a plurality of parallel endless conveyors for carrying articles forwardly, said conveyors being divided into a plurality of groups corresponding to the number of tiers to be packed, gate means disposed adjacent the discharge end of said conveyors for restraining forward movement of said articles, means for periodically opening said gate means to simultaneously release one article from each conveyor, a transverse conveyor, a plurality of package forms carried by said transverse conveyor, said package forms having an open top and a bottom movable toward and away from said top, means for intermittently moving said transverse conveyor in timed relationship with the opening of said gate to dispose

a package form in alignment with each group of conveyors when said transverse conveyor is stationary, means for pushing the articles from each group released from said endless conveyors into

- 5 the open top of a respective package form in timed relationship with the stopping of said forms to position a tier of articles in said form resting upon said movable form bottom, means for moving said transverse conveyor into consecutive alignment with each group to receive tiers of said articles, means for moving the form bottom away from the top after receipt of each tier of articles to superimpose said tiers in said forms, and means for transferring the articles from each form into a carton.

15 15. A packaging machine for packaging a predetermined number of articles in tiers in a carton which comprises, a plurality of parallel endless conveyors, for carrying articles forwardly, said conveyors being divided into a plurality of groups corresponding to the number of tiers to be packed, gate means disposed adjacent the discharge end of said conveyors for restraining forward movement of said articles, means for periodically opening said gate means to simultaneously release one article from each conveyor, a transverse conveyor, a plurality of package forms carried by said transverse conveyor, said package forms having an open top and a bottom movable toward and away from said top, means for intermittently moving said transverse conveyor in timed relationship with the opening of said gate to dispose a package form in alignment with each group of conveyors when said transverse conveyor is stationary, means for pushing the articles from each group released from said endless conveyors into the open top of a respective package form in timed relationship with the stopping of said forms to position a tier of articles in said form resting upon said movable form bottom, means for moving said transverse conveyor into consecutive alignment with each group to receive tiers of said articles, means for moving the form bottom away from the top after receipt of each tier of articles to superimpose said tiers in said forms, means for interposing a separator between each tier of articles, and means for transferring the articles from each form into a carton.

50 16. A packaging machine for packaging a predetermined number of articles in tiers in a carton which comprises, a plurality of parallel endless conveyors for carrying articles forwardly, said conveyors being divided into a plurality of groups corresponding to the number of tiers to be packed, gate means disposed adjacent the discharge end of said conveyors for restraining forward movement of said articles, means for periodically opening said gate means to simultaneously release one article from each conveyor, a transverse conveyor, a plurality of package forms carried by said transverse conveyor, means for intermittently moving said transverse conveyor in timed relationship with the opening of said gate, means for progressively disposing package forms in respective alignment with said conveyors when said transverse conveyor is stationary, means for simultaneously moving the articles from each group released from said endless conveyors into a respective package form in timed relationship with the stopping of said forms to position tiers of articles in said forms in superimposed relationship to each other, means for interposing a separator between each tier of articles in each

form, and means for transferring the articles from each form into a carton.

17. In a feed conveyor, an endless continuously moving conveyor having a feed end and a discharge end for carrying articles forwardly, a normally closed gate positioned adjacent the discharge end of the conveyor for restraining forward movement of articles on said conveyor to cause said articles to accumulate on said conveyor in substantially contiguous columnar form, means for intermittently opening said gate to release an article from the discharge end of the conveyor, and a feeler positioned adjacent an intermediate portion of said conveyor responsive to predetermined maximum spacing of articles and means actuated by said feeler to render said gate opening means inoperative.

18. In a packaging machine for packaging articles in tiers in a package form, a conveyor, a package form carried by said conveyor, pushers for moving tiers of articles into said package form in superimposed relationship, and means for interposing a separator between each tier of articles in said form, said separator interposing means comprising means for feeding a predetermined length of separator material above said form means for cutting said separator material to form a separator, and means upon said pusher

and cutting means for cooperatively depositing said separator in said form.

19. In a packaging machine for packaging articles in tiers in a package form, a conveyor, a package form carried by said conveyor, pushers for moving tiers of articles into said package form in superimposed relationship, and means for interposing a separator between each tier of articles in said form, said separator interposing means comprising means for feeding a predetermined length of separator material above said form means for cutting said separator material to form a separator, and interdigitating resilient means upon said pusher and cutting means for engaging said separator and depositing it in said form.
